UNITED STATES PATENT OFFICE.

EDWIN J. WALKER, OF PHILADELPHIA, PENNSYLVANIA, ASSIGNOR OF ONE-HALF TO EDWIN J. WALKER, JR., AND SHARSWOOD BRINTON, OF SAME PLACE.

BIN.

SPECIFICATION forming part of Letters Patent No. 550,900, dated December 3, 1895.

Application filed June 17, 1895. Serial No. 553,015. (No model.)

To all whom it may concern:

Be it known that I, EDWIN J. WALKER, of Philadelphia, Pennsylvania, have invented a new and useful Improvement in Bins, of 5 which the following is a description, referring to the accompanying drawings, which form a part of this specification.

The invention relates to pivotal or tilting bins which can be placed or built into a counter for grocery, drug, feed, seed, or other stores, or may be built into the walls or otherwise adapted to use in granaries, stables, kitchens, pantries, and many other places.

The object of the invention is to make a 15 balanced bin that when in its closed position shall be flush with the face of the counter or other fixture in which it is set and shall present a neat appearance, effectively excluding dust, dirt, vermin, and other foreign 20 matter. The bin is so balanced that it may be drawn out and tilted forward or replaced in position by a very small force, being retained by its own weight in both its closed and opened positions. When open, also, the 25 bin is so fitted that it entirely excludes dust, dirt, vermin, &c. In addition the objects of this invention include economy of space, simplicity of construction, durability, and rigidity in position. Each bin is so mounted 30 that it cannot be shifted sidewise or bind with the bin or portion of the fixture adjacent yet it may be readily entirely removed from the fixture and cleaned and replaced.

To these and certain other purposes, which 35 will appear more clearly from the following description, the invention is embodied in the bin and its several features constructed, combined, arranged, and used substantially in the manner hereinafter described, illustrated, 40 and claimed.

In the drawings, Figure 1 is an isometric projection showing three bins arranged in a counter. Fig. 2 is a transverse section of the counter, showing the arrangement of partial 45 partitions between the bins. Fig. 3 is a transverse section through a bin, showing the pivotal connection on which it rests and turns; and Fig. 4 is an isometric projection of the metal joint or pivotal connection as arranged 50 for two or more bins.

Throughout the drawings like letters and numerals of reference indicate like parts.

The upper surface of the counter is shown at C, the bins at B, the sectional partition at P, and the hinged or swinging joint at J. 55 In this illustration of my invention I have shown the three bins arranged in a grocery-store counter. The pins are built of the cross-section shown in Fig. 3, the front b neatly fitting the space occupied by the bin in the rear face of the counter, and adjacent bins abutting directly, as indicated, without space or partition between their faces. The bottom of the bin is provided with the hinge-iron j, containing the two downward-extending pivotal projections 1, of the shape clearly shown in Fig. 3, which enter into registering recesses 2 into the plate or iron j'. These details are also clearly shown in perspective in Fig. 4. Each bin is provided with one hinge-iron j, while the plate j' is common to the three bins and secured to the edge of the bottom of the counter, as seen in Figs. 1 and 3. Owing to the shape of the bin its weight tends to hold it closed and press it firmly against 75 the counter when shut; but when open the balance is such that it remains open, requiring, however, but slight pressure to overbalance it and shut it up.

The front b of the pin projects slightly at 80 each side, as at 3, Fig. 1, so that when closed it rests against the partition P, Fig. 2, as at 4. When in this position, the upper line of the bin comes just above the lower edge of the partition P and the upper rear edge of the 85 bin 5 lies close to the inner or front wall of the counter. Where the counter is broad, the bin need not extend all the way in to this wall; but for shallow counters it is preferable.

It will now be seen that in its closed position the bin is covered and inclosed entirely by means of the top of the counter C, which meets the front edge of the bin, the partitions P or the end of the counter, which close the bins at the side, and the front wall of the 95 counter F, which meets and closes the rear edge of the bin. When, however, the bin is drawn out or opened, it turns upon the joint or hinge J and assumes the position shown in dotted lines in Fig. 3, the rear wall b' of the 100

bin coming to an approximately vertical position and the edge 5 coming into contact either with the top of the counter, as at 6, or with the stop 7. This stop 7 may be so placed that in its closed position the front wall of the bin b rests against it and takes the shock when the bin is slammed or closed quickly. This stop therefore would relieve the end of the partitions P from the continual jars when bins are closed. All these stops may be faced with rubber and the action of the bin rendered noiseless.

In its open position the rear face of the bin b', resting against the stop 7 or against the top of the counter, covers the bin at that edge and prevents the grain or other material within the bin from being thrown over the rear edge; also, in its open position the bin forms a tight joint at the corner J and prevents rats or other vermin from getting underneath. By this the invention is distinguished from other bins, in which the front edge is tilted downward when the bin is drawn or tilted forward, and very often when such a bin is used in counters it may be dropped onto the toes of the salesman or other person behind the counter.

It will be seen that the hinge J, while of the simplest possible construction, at once locates the pivotal point at the very edge of the bin, so that the bin turns upon that point instead of moving forward or downward. At the same time the projections 1, entering in the recesses 2, prevent any displacement of the bin, keeping it always in its proper position and obviating the jamming or grinding against adjacent bins, an objection very common in some constructions in general use.

In the broader aspects of the invention it is of course not limited to the precise form of joint shown, as the same action in a pivoted or tilting bin may be accomplished in other ways, provided the joint be located in accordance with the principles just explained; but by the form of joint shown the bin is held firmly in position when open and when closed

and the joint cannot be disconnected. In all positions, moreover, the weight of the bin keeps the joint together; but when the bin is half opened it may be raised. It is then free to be raised slightly, drawing the projections 1 out of the recesses 2, disengaging the joint, and leaving the bin to be entirely removed for cleaning or repairs. For druggists and fancy grocers the invention may be applied to smaller bins or boxes arranged upon the wall and provided with transparent or other ornamental front. Any bin or box may be readily taken down by tilting it forward slightly, raising it, and so removing it. When in place, whether open or closed, it cannot be thrown out by any jar.

I purposely omitted the many modifications which may be made in this application without departing from its principles, because to set them forth at length would obscure rather than make clear the more essential features.

I claim, however, and desire to secure by these Letters Patent of the United States, together with all such changes and improvements as may be made by mere skill, and with only the limitations as expressed or by law implied in view of the related arts, as follows:

In combination with the counter, wall, or other mounting, the pivotal bins mounted therein, the detachable pivotal joint or connection therefor at the front lower edge of the bin and consisting of one or more projections fitting into corresponding recesses, the said bin substantially forming a continuation of the wall or face of the said mounting and fitting securely therein, when closed, but free to be raised therein and detached therefrom when partially open, substantially as set forth.

In testimony whereof I have hereunto set my hand, at Philadelphia, this 6th day of June, A. D. 1895.

EDWIN J. WALKER.
